ROTATING AIR DISTRIBUTING OUTLETS

Harry S. Wheller, Elizabeth, N. J., assignor to L. J. Wing Mfg. Co., Linden, N. J., a corporation of New Jersey

Application June 28, 1952, Serial No. 296,119

12 Claims. (Cl. 98—40)

This invention relates to rotating air distributors. It is particularly directed to the distribution of air supplied to rooms or other spaces for ventilating, cooling, or heating.

An object of this invention is to provide means for assuring against (or preventing) occupants of, or goods being processed in, spaces to which air is being supplied, being subjected to constant drafts of air from fixed openings or outlets through which air is delivered to such space.

A further object of this invention is to provide an air distributor of the character described which will rotate by influence of air forced through it in combination with means for retarding and controlling the rate of rotation of the distributor.

The distributor consists of a chamber arranged to rotate horizontally on a vertical axis, said chamber to be provided with one or more outlets so placed that as the air leaves them the chamber is caused to rotate opposite to the direction in which the air is discharged. Thus, the direction of each outlet is constantly changing and, therefore, any occupant, or goods in process, will not be subjected to a constant uninterrupted draft, but, instead, to a gentle motion of air at interrupted intervals, the frequency depending upon the rate of rotation of the chamber, which is controllable and may be readily increased or decreased to suit conditions.

The outlets are provided with adjustable vanes permitting delivery of air horizontally or at any desired downward angle to the perpendicular.

Air previously cooled, or heated, or otherwise treated as dehumidified, etc., is carried to the rotatable chamber from the point where the air is treated through the duct to which the distributor is attached, and is thus forced through the outlets.

Any number of such distributors may be applied to a given space, but one distributor of this type will effect uniform air distribution over a much wider area than prior fixed outlet types of distributors, thus reducing the number of distributors required, and, consequently, reducing the cost of the system.

The number of outlets per distributor depends largely upon the area or space to which the air is to be supplied—the larger the area the more outlets.

In the case of more than one outlet, the downward angle of delivery is adjusted differently for each outlet. The outlets which are to project air the greatest distance are set at a less angle to the horizontal, and those covering the inside area are adjusted to progressively greater angles.

In the case of distributors with multiple outlets the size of the outlets may be varied; those intended to project the air the greatest distance would be larger, and the others progressively smaller.

Many distributing outlets, as heretofore made, when used to deliver cooled air to rooms or other spaces, function primarily to spread all or portions of the air it

2

distributes horizontally over a reasonably wide area at the ceiling, from which, theoretically, it is supposed to drop of its own weight and thus cool the room; however, if the air which is spread horizontally by such outlets strikes a wall it will deflect downwardly and anyone located near the wall will be subject to an objectionable constant and uninterrupted draft. The same is also true if the air strikes as column or other obstruction.

When such prior outlets as used for cooling are used for heating, that is, for delivery of heated air to the rooms, warm air delivered horizontally at the ceiling does not reach the floor or working level unless in its horizontal travel it does strike a wall or column, in which case it will be deflected down the wall to the floor, thus subjecting anyone or anything within the area of influence to a constant draft or cloud of heated air above normal room temperature, or if the outlet were so far away from a wall or column that its velocity was spent before reaching the wall, heated air would never reach the floor but would accumulate at the ceiling, thus the temperature at the ceiling would always be much warmer than the air at the floor or working level. In other words, such outlets allow one's feet to remain cold while the upper portions of the body would be overseated.

It is, therefore, a further object of this invention to provide an improved air distributor which rotates and has one or more outlets, and is so constructed as to eliminate the above objections of prior outlets. The air distributor embodying the invention is so constructed as to deliberately project air streams angularly downward to the floor so that the heated air will be delivered to the floor to dispose the cold (or cooler) air from the floor, but in doing so would not subject the occupants, or any contents of the room to constant uninterrupted drafts or blasts of air. In cooling, the outlet embodying the invention would have all of the advantages so far as the elimination of objectionable constant uninterrupted drafts are concerned, plus the added cooling effect of air in motion, thus producing a higher degree of cooling comfort with a given amount of coolant, and, therefore, at less cost.

Yet a further object of this invention is to provide a strong, rugged and durable revolving air distributor, which shall be simple and positive in operation, relatively inexpensive to manufacture, which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention:

Fig. 1 is a vertical axial cross-sectional view of a revolving air distributor embodying the invention;

Fig. 2 is a cross-sectional view taken on the line 2—2 of Fig. 1;

Fig. 3 is an enlarged cross-sectional view taken on the line 3—3 of Fig. 2;

Fig. 4 is a cross-sectional view taken on the line 4—4 of Fig. 3;

Fig. 5 is a cross-sectional view taken on the line 5—5 of Fig. 4;

Fig. 6 is a cross-sectional view taken on the line 6—6 of Fig. 3;

Fig. 7 is a view similar to Fig. 6 but showing the retarding device in an adjusted position;

Fig. 8 is an outside view of the retarding device employed in the structure shown in Fig. 1;

Fig. 9 is a view similar to Fig. 1 but illustrating a modified construction for use under different conditions than the device of Fig. 1, such as in rooms of greater height;

Fig. 10 is a cross-sectional view taken on the line 10—10 of Fig. 9;

Fig. 11 is a cross-sectional view taken on the line 11—11 of Fig. 10;

Fig. 12 is a cross-sectional view taken on the line 12—12 of Fig. 11;

Fig. 13 is a view similar to Fig. 1 and illustrating yet another modified construction;

Fig. 14 is a cross-sectional view taken on the line 14—14 of Fig. 13;

Fig. 15 is a view similar to Fig. 13 and illustrating still another modified construction; and

Fig. 16 is a cross-sectional view taken on the line 16—16 of Fig. 15.

Referring now in detail to the drawings, 10 designates a revolving air distributor embodying the invention for distributing air supplied to rooms or other places for ventilation, heating, and/or cooling.

The distributor 10 is suspended for rotation from a stationary support 11 which may be attached to an air duct 12 or to other means to bring air to and force it through the outlet. The air duct 12 is hence shown in the drawings merely as representative of a means for conveying air for distribution.

The stationary support 11 comprises an annular member 13 having a downwardly projecting cylindrical portion 14 from which extends upwardly an outwardly curved portion 15 formed with a horizontal flange 16. Flange 16 may be attached to the bottom wall 12a of the duct 12 to surround an opening 17a therein, in any suitable manner or to any other means which supplies a stream of air to be blown downwardly through said member 13.

Fixed with the lower end of the cylindrical or annular portion 14 is a spider 17 comprising a hub 18 from which extend a plurality of radial spokes 19 connected at their ends to a ring 20 which fits within said cylindrical portion and which is attached thereto in any suitable manner. The hub 18 is formed with a central vertical screw threaded through opening 21. Extending through and screwed within opening 21 is a shank 22 of a bolt 22a having a head 23 at its lower end. A nut 24 screwed to the upper end of the bolt shank 22 rests on the hub 18.

Mounted on the bolt 22a and supported for axial rotation thereon, is the rotating or revolving air distributor 10. The same comprises a casing 25. Said casing comprises an upper cylindrical wall 26, the upper end of which telescopes with the lower end 14 of supporting member 11. Fitted within said wall 26 below the upper end thereof, is a spider 27 spaced below spider 17. The same comprises a center hub sleeve 28 centered with hub 18 and connected by radial spokes 29 to a circular ring 30 disposed within the cylindrical wall 26 and fixed thereto in any suitable manner. Within the center sleeve 28 is a thrust ball bearing 31 through which the shank of the bolt 22a passes. Said ball bearing 31 rests on the head 23 of the bolt and connects the sleeve for rotation about the bolt 22a. Thus, the casing 25 is supported for rotation by the bolt.

Said cylindrical wall 26 is formed with an annular indented groove 34, for the purpose hereinafter appearing. Extending from the cylindrical wall 26 are a plurality of similar horizontal wall portions or wings 35, four of such wings being shown for the purpose of illustration. Said wings 35 have spirally shaped outer edges 36 extending outwardly from the wall 26. Said wings 35 also have straight end edges 37 which form acute backwardly sloped angles with radial lines passing through the portions of said edges closest to the wall 26. Extending downwardly from the outer edges 36 of wall 35 are curved walls 38 extending spirally and following the curvature of edges 36.

At the bottom of the casing is a central circular wall

portion 41 from which extend wings 42 similar to and aligned with wings 35 and extending to the curved walls 38. The curved walls 38 have vertical straight edges 44 and the bottom wall portions 42 have straight end edges 45.

Wings 35 and 42 and interconnecting wall 38 form an outer air nozzle 48. The edges 37, 44, 45 of each nozzle 48 are disposed in a single vertical plane.

It will now be understood that four air outlets or nozzles 48 are formed through which air must pass out of the casing. These nozzles are slightly overlapped as shown in the drawing.

It will now be understood that air passing through duct 12 and down through the fixed supporting member 11 will 10 pass into the casing 25 and out through the nozzles 48 thereby causing self rotation of the distributor 10 about its axis in the direction of the dotted arrows (Fig. 2), due to back pressures creating a torque on the outlet.

Means is provided to deflect the streams of air coming 20 from the nozzles in downwardly inclined directions as the outlet rotates. To this end there may be mounted across the mouth of each nozzle a plurality of parallel transverse downwardly and outwardly inclined deflecting 25 vanes 50. These vanes may be adjustable if desired and cause the stream of air to be deflected in downwardly and outwardly inclined directions as the outlet rotates.

When the distributor 10 is used for heated air, the 30 heated air will be delivered downwardly to the floor to dispose the cold air from the floor. When used for cool air, the distributor 10 will produce the effect of reducing the temperature of the room and a cooling effect caused by the downwardly projecting rotating column of air. In any event, such an outlet will remove the objection to fixed 35 outlets which send out streams of air horizontally and which cause an objectionable constant and uninterrupted draft when used for distributing air for cooling or heating, and which when used for distributing air for heating results in higher overhead temperature than the temperature at the floor or working level.

Means is provided to retard and control the self rotation of the distributor 10. To this end there is attached 40 to member 13 in any suitable manner, a bracket 51. Said bracket 51 has an arm 52 supporting a casing 53. Said casing 53 has a bottom wall 54 from which extends upwardly 45 cylindrical wall 55. Extending upwardly from the bottom wall 54 is a central integral sleeve 56 in which is fixed a vertical bushing 57 open at the top. Said bottom wall 54 is also formed with an integral sleeve 58 offset 50 from the axis and formed with a through-opening in which is received a fixed bushing 59. Sleeve 58 extends above and below bottom wall 54 and bushing 59. Extending upwardly from the bottom wall 54 is an upstanding vertical sleeve 60 closed at the bottom and open at the top. Fixed within the sleeve 60, for the purpose hereinafter appearing, is a bushing 61. The upper ends of the sleeves 58 and 60 and their bushings are well below the upper end of the cylindrical wall 55 and substantially at a common level. Sleeve 56 and its bushing extend above sleeves 58, 60.

The cylindrical wall 55 is counterbored at its upper 60 end as shown at 63, and the inner surface of the counterbore is formed with an annular intermediate internal groove 64 for the purpose hereinafter appearing.

Said bottom wall 54 is furthermore formed with a 65 depressed part-cylindrical recess 65 disposed perpendicular to a plane passing through the axes of sleeves 56 and 60. Rotatably mounted with the bushing 59 is a vertical pin 66. Riveted to the upper end of the pin 66 is a pinion 67 which rests on sleeve 58. The pin 66 projects below sleeve 58 and attached to said projecting end of said pin by means of set screws 68 is a pulley 69 disposed in the plane of the annular groove 64 in the cylindrical wall 55 of casing 25. Interconnecting the 70 pulley 69 with the groove portion 34 is a flexible belt 75

70 which in the present instance is shown in the form of an endless coil spring.

It will now be observed that as the distributor 10 rotates, pulley 69 will also be rotated for rotating the pinion or gear 67.

Mounted for rotation within the bushing 61 is a vertical pin 71. Fixed to the upper end of the pin 71 is a smaller lower pinion 72 meshing with the pinion 67, and an upper larger pinion 73. The latter meshes with the pinion 74 fixed to the upper end of pin 75 rotatably mounted within the bushing 57.

It will now be understood that rotation of the pulley 69 will cause rotation of the pin 75.

Fixed to the top of pin 75 and disposed above pinion 74 is a horizontal circular disk 76 preferably made of copper. The outer diameter of the disk 76 is somewhat smaller than the inner diameter of cylindrical wall 55 of casing 53.

Fixed within the recess 65 is a permanent magnet 77 of horseshoe shape. The middle curved portion 78 of said magnet is fixed within the recess 65 and said magnet has upwardly extending arms 79 and 80, the upper ends of which are located just below the level of the disk 76.

Mounted within the counterbore portion 63 of the casing is a cover plate 81 and said cover plate is held in place by a split ring 82 which fits within the internal groove 64. The annular position of the cover plate 81 may be adjusted by means of a handle 84 having one end 85 fixed to the cover plate and another portion 86 extending over the cylindrical wall 65 and projecting downwardly. Attached to the underside of plate 81 is a steel plate 87. The steel plate 87 and the handle 85 may be attached to opposite sides of the plate 81 by means of screws 88.

It will now be understood that rotation of the disk 76 will be retarded by reason of the magnet flux passing therethrough from the magnet 77 to the steel plate 87. In such manner the rotation of the outlet is retarded. The degree of retardation may be adjusted by grasping the handle portion 86 and turning the disk 81 to bring the steel plate 87 closer or further away from the upper ends of the magnet legs 79 and 80. The retarding device 53 thus serves to prevent too rapid a rotation of the outlet.

A scale 90 may be placed on the outside of the cylindrical wall 55 to cooperate with the handle portion 86 which serves as a pointer. The lower end of the handle portion 86 may come to a point for this purpose.

In Fig. 7 the steel plate is shown in a position offset from the position shown in Fig. 6 to illustrate the adjustability.

In Figs. 9, 10, 11 and 12 there is shown a revolving air distributor 10a embodying the invention and illustrating a modified construction. The distributor 10a is mounted on a fixed supporting member 11 similar to member 11 shown in Fig. 1. Said supporting member 11 may be attached to any means for producing a stream of air downwardly therethrough. The distributor 10a comprises a spider 27 similar to the spider 27 of Fig. 1 and mounted for rotation on a bolt 22a fixed to the hub 18 of a spider 17 fixed within the throat 13 of member 11. Fixed to the ring 30 of the spider 27 is the upper cylindrical wall 100 of a casing 101. The cylindrical wall 100 is formed with an annular groove 102 for the purpose hereinafter appearing.

Extending downwardly from the cylindrical wall 100 are a pair of similar symmetrically disposed nozzles 103 inclined downwardly and outwardly in opposite directions and disposed on opposite sides of a vertical plane passing through an axis of the bolt 22a. Nozzles 103 may taper slightly toward their ends, being frusto conical in shape.

Thus air passing downwardly through member 11 will be directed downwardly and outwardly through the nozzles 103. Furthermore, the distributor 10a will have self rotation under the influence of air blown therethrough by reason of the fact that the air emerges from the nozzles

in directions which are not radial with respect to the axis of the outlet.

Means is provided to control and retard the rotation of the distributor 10a. To this end there is fixed to member 13 in any suitable manner a bracket 105. Said bracket 105 is formed with a horizontal radial arm 106 provided with a sleeve 107 at its outer end. Received within the sleeve 107 is a stem 108, fixed thereto by a set screw 109. At the lower end of the stem 108 is a flat annular disk 110 formed with a peripheral upwardly extending flange 111 having external screw threads 112. Screwed to the threaded portion 112 is a cylindrical wall 113 of a casing 114. Said casing 114 has a bottom wall 115. The stem 108 is formed with an eccentrically located vertical through opening 116. Extending through said opening 116 and rotatably mounted therein is a pin 117. The lower end of the pin 117 is adjacent the upper surface of the bottom wall 115. Fixed to the upper end of the pin 117 as by set screw 118 is a pulley 119 connected by a coil flexible belt 120 to the grooved portion 102 of the distributor 10a.

It will now be understood that as the outlet 10a rotates due to the influence of air passing therethrough, it will cause the pulley 119 to rotate, thereby also rotating the pin 117. Fixed to the lower end of the pin 117 and located within the casing 114 and between the bottom wall 115 and the wall 110 is a rotor 121 coaxial with the pin 117 and being substantially tangent to the inner surface of the cylindrical wall 113. The top surface of rotor 121 is below the undersurface of wall 110.

The rotor 121 is formed with a plurality of vertical U-shaped notches or slots 122 tangent to a common circle coaxial with the rotor. Within each slot or notch 122 is a vertical sleeve or tube 123 which may slide in and out through the slot. Within the chamber 124 formed in the casing 114 between walls 113, 115 and 110 is a liquid such as oil. As the rotor 121 is rotated, the sleeves 123 are carried round and round and move inwardly and outwardly alternately through the slots 122. During such rotation the chambers formed between rotor 121 of the casing wall 113 on opposite sides of the tubes 123, vary in volume, so that the oil must flow from one chamber to another. The oil flows from one chamber to another by passing above the rotor 121 and above the tubes 123 through the space below wall 110, causing retarding of the rotor, and hence a retarding movement of the pulley 119 and casing 109.

A rubber cap 125 may be fitted over the top of the casing 114 and it is formed with a central opening through which the stem 108 passes. Oil may be inserted into the casing through an inclined opening 126 passing through stem 108 and communicating with a counterbore 127 at the bottom of wall 110.

Furthermore, air holes 128 may be provided in the top wall 110 to permit trapped air to escape. There is thus provided a hydraulic brake for retarding and controlling the movement of the outlet 10a.

In Figs. 13 and 14 there is shown a revolving air distributor 10b suspended for rotation from a stationary support 11. The outlet 10b is similar to the distributor 10 except that it is provided with only two nozzles 130 instead of four nozzles 48 as in the latter outlet. Rotation of the distributor 10b may also be controlled by a device 53 belted to the outlet casing by belt 70 in the same manner as in the modification shown in Figs. 1 to 8.

In Figs. 15 and 16 there is shown a revolving air distributor 10c similar to the distributor 10 except that it is provided with three nozzles 131 instead of four nozzles. It may be provided with a magnetic type of retarder or brake shown in Figs. 1 to 8 or other form of retarder.

While there is shown distributors of two, three or four nozzles or outlets, the distributor may have only 75 one nozzle or outlet. Thus an air distributor may be

provided such as shown in Fig. 14 but with only one nozzle or outlet for use in a very small room requiring a very small quantity of air. Such construction would give required power to rotate the outlet and increase the projection of the column of air. Such a distributor would also be provided with retarding means as shown.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings, is to be interpreted as illustrative and not in a limiting sense.

Having thus described my invention, I claim as new and desire to protect by Letters Patent of the United States:

1. A fixed support, an air distributor comprising a casing having one or more outlet nozzles, means to mount said distributor on said support for rotation about its axis, a casing fixed relative to said support, a rotary member within said last mentioned casing, a pulley attached to said rotary member for rotation therewith, means for belting said pulley to said distributor, and means to retard the rotation of said rotary member within the last mentioned casing.

2. A fixed support, an air distributor comprising a casing having one or more outlet nozzles, means to mount said distributor on said support for rotation about its axis, a casing fixed relative to said support, a rotary member within said last mentioned casing, a pulley attached to said rotary member for rotation therewith, means for belting said pulley to said distributor, means to retard the rotation of said rotary member within the last mentioned casing, and vanes within said nozzles to deflect air downwardly and outwardly.

3. In combination, a support, an air distributor mounted thereon for rotation about its axis, said distributor being provided with one or more outlet nozzles to cause self-rotation of the distributor when air is forced through the distributor, a casing, means to fix said casing to said support, a copper disk mounted for rotation in said fixed casing, means connected with the air distributor to cause rotation of said disk when the distributor is rotated, a fixed magnet within the casing and adjacent said disk, and on one side thereof.

4. The combination of claim 3, in combination with a cover mounted for rotation on said fixed casing and at the other side of said copper disk, and a member comprising iron fixed to the cover, said cover being rotatable relative to said fixed casing to bring said member into and out of alignment with respect to said fixed magnet.

5. The combination of claim 4, and a handle fixed to said cover to facilitate rotation thereof.

6. In combination, a support, an air distributor mounted thereon and provided with air distributing nozzles for rotation about its axis, said distributor being provided with means to cause self-rotation of the distributor when air is forced through the distributor, a cylindrical casing, means to fix said casing to said support, a copper disk mounted for rotation within said casing about the axis of said casing, a pin mounted for rotation on said casing and passing through a wall of said casing and being offset from the axis of said casing, means to connect said pin for rotation to said distributor, a gearing interconnecting said disk and said pin and disposed within said casing, a permanent magnet fixed within said casing

and disposed below said disk, a cover on the upper end of the casing, and a member comprising iron fixed to the underside of the cover in opposed relation to the fixed magnet.

5 7. The combination of claim 6, said cover being rotatable with respect to said casing, and a handle fixed to the cover and overhanging one side of the cylindrical casing.

8. A fixed support, an air distributor comprising a 10 casing having one or more outlet nozzles, means to mount said distributor on said support for rotation about its axis, a casing fixed to said support, a rotary member within said casing, a pulley attached to said rotary member for rotation therewith, means for belting said 15 pulley to said distributor, means to retard the rotation of said rotary member within said casing, and means to control the rate of retardation of said rotary member by adjustment of said means of retardation.

9. The combination of claim 8, and said means of retardation including a rotary copper disc within said casing and connected for rotation to said rotary member, and a magnet adjacent said disc.

10. In combination, a fixed support, an air distributor 20 having one or more outlet nozzles, means to mount said distributor on said support for rotation about its axis, said nozzles being positioned to cause self rotation of said distributor when air is forced through said distributor, a member mounted for rotation on a fixed axis relative to said support and outside of said distributor, drive 25 means connecting said distributor to said rotary member for rotating said rotary member continuously upon said distributor being rotated, means to retard the rotation of said rotary member for retarding rotation of said distributor, and means affecting the rotary member to vary 30 the rate of retardation.

11. In combination, a support, an air distributor 35 mounted thereon for rotation about its axis, said distributor being provided with one or more outlet nozzles arranged to cause self rotation of the distributor when air is forced through the distributor, a copper disc, supporting means to mount said disc on said support for 40 rotation about a fixed axis, means connected with the distributor to cause rotation of said disc when said distributor is rotated, and a magnet mounted on said supporting means adjacent said disc for retarding rotation 45 thereof.

12. The combination of claim 11, said magnet being on one side of said copper disc, a member comprising iron on the other side of said copper disc, and means on 50 said supporting means to mount said member for movement to bring said member into and out of alignment with respect to said magnet for varying the rate of retardation of said disc.
